UNITED STATES PATENT OFFICE

PIETRO B. VISCONTI, OF NEW YORK, N. Y.

DESIGN FOR AN ELECTRIC RADIATOR

Application filed August 1, 1931. Serial No. 40,749. Term of patent 14 years.

To all whom it may concern:

Be it known that I, PIETRO B. VISCONTI, a citizen of the United States, residing in the borough of Manhattan, city, county and State of New York, have invented a new, original, and ornamental Design for Electric Radiators, of which the following is a specification, reference being had to the accompanying drawings, forming part thereof.

Fig. 1 is a front elevation of an electric radiator, showing my new design, the back of the radiator being a flat plate, and

Fig. 2 is a reverse plan view of an electric radiator, showing my new design.

I claim:

The ornamental design for an electric radiator, as shown and described.

PIETRO B. VISCONTI.
